UNITED STATES PATENT OFFICE

OTTO W. BRANDES, OF MILWAUKEE, WISCONSIN

WINDOW SCREEN

Application filed July 20, 1928. Serial No. 294,215.

This invention relates to window screens and is particularly directed to a screen adapted for use in automobile windows, although obviously the screen may be used in other places, if desired.

Objects of this invention are to provide an expansible screen which is adapted to automatically fit itself or adjust itself to windows of different sizes, which automatically expands and holds itself tight against rattling, which holds itself in place without additional fastening means, which does not require any alteration of the automobile window casing, and which holds the sides and top and bottom portions of the screen in intimate contact with the corresponding portions of the window casing whether or not the edges of the window casing are in parallelism.

Further objects of this invention are to provide a novel form of screen, all of whose portions are formed of metal, and to provide a construction which is simple and economical to produce.

An embodiment of the invention is shown in the accompanying drawings in which:

Figure 1 is a view of the screen looking from the outside of an automobile window;

Figure 2 is a sectional view on the line 2—2 of Figure 1 drawn to an enlarged scale;

Figure 3 is a sectional view on the line 3—3 of Figure 1.

Referring to the drawings, it will be seen that the screen comprises a wire mesh member 1 which extends between channel-shaped inner rectangular frame members 2. The structure may be reenforced or completed by means of metal strips 3 which are positioned inside the inturned edges of the screen, as shown most clearly in Figures 2 and 3.

The parts are brazed, welded, or soldered together, or otherwise secured, so as to hold the wire mesh or screen portion stretched and taut under all conditions. The rectangular member 2 is preferably a unitary structure throughout, as is apparent from Figure 1, and is, as stated, formed of a channel shaped metal member.

The outer rectangular portion of the

screen is formed of four corner members, indicated by the reference character 4, and four longitudinally extending straight portions 5 which fit within or telescope within the ends of the corner members. The corner members are provided with inwardly turned lips 6 which fit over the edges of the straight sections 5 and thus slidably retain themselves associated with the corner members.

From the construction thus far described, it is apparent that the outer rectangular member may be enlarged, as required, or extended in a vertical or horizontal direction. Further, it is apparent from the overlapping provided in the telescopic connection or fit of the inner rectangular member within the outer rectangular member, that this overlap is maintained throughout a considerable range of adjustment of the outer rectangular frame member.

A plurality of bowed springs 7 are secured at their central portions within the channel-shaped inner rectangular frame member 2, as shown most clearly in Figure 1, and the ends of the springs are placed within and bear upon the outer rectangular frame. Preferably, the ends of the springs are slightly upturned, as indicated at 8, to provide rounded extremities so that these ends may freely ride within the outer rectangular frame member.

Thus the springs tend to force the outer rectangular frame member outwardly, both horizontally and vertically. In this manner, the outer rectangular frame member is held in binding or close fitting engagement with the corresponding portions of the window casing 9 of the automobile. Preferably, the screen is positioned outside of the glass panel 10, as shown in Figures 2 and 3.

The outer rectangular frame member is provided with securing clips 11 which are curved to fit over the corresponding edge of the window casing and which are provided with downturned inner ends 12 which fit between the resilient packing 13 and adjacent portion of the window casing, to thus retain the screen against dislodgement.

It is apparent that a very simple and serviceable type of expansible screen has been

provided which is so constructed that it will hold itself in binding or tight engagement with the window casing and will adjust itself to variations in size of the windows.

5 Further, it will be seen that no additional fastening means whatsoever are required, but that the expansible screen is so constructed that it automatically locks itself in place
10 against dislodgment.

15 It will be seen, therefore, that a very simple type of expansible screen has been provided which although having the characteristics enumerated above is nevertheless free from any complicated structure or any construction which would mar its attractive appearance.

20 Although the invention has been described in considerable detail, such description is intended as illustrative rather than limiting as the invention may be variously embodied and as the scope of such invention is to be determined as claimed.

I claim:

25 1. An expansible screen comprising an inner rectangular frame channel-shaped in cross section, a wire mesh member carried by said frame and secured to the intermediate wall thereof, an outer frame formed of
30 channel sections telescopically receiving said inner frame, and springs interposed between said frames, said outer frame being composite and having its parts telescopically related.

35 2. An expansible screen comprising an inner rectangular frame channel-shaped in cross-section, a wire mesh member carried by said frame and secured to the intermediate wall thereof, an outer frame formed of
40 channel sections telescopically receiving said inner frame, and springs interposed between said frames, said second frame being formed of corner portions and straight sections between the corner portions and telescopically
45 fitted to said corner portions.

50 3. An expansible screen for automobile windows comprising a rigid inner frame channel-shaped in cross-section, a wire mesh stretched across said frame and secured to the intermediate wall thereof, an outer frame formed of channel shaped corner portions and channel straight portions telescopically related to said corner portions, said outer frame telescopically holding and surrounding said inner frame, springs interposed between said inner and outer frames, and clips carried by said outer frame and adapted to lock said outer frame to a window casing.

55 In testimony that I claim the foregoing I
60 have hereunto set my hand at Milwaukee, in the county of Milwaukee and State of Wisconsin.

OTTO W. BRANDES.
